(57) **CLAIM**

The ornamental design for a roll up character pillow and sleeping bag combination, as shown and described.

DESCRIPTION

FIG. 1 is a front perspective view of a roll up character pillow and sleeping bag combination in accordance with my new design;

FIG. 2 is a front elevation view thereof;

FIG. 3 is a rear elevation view thereof;

FIG. 4 is a right side elevation view thereof, a left side elevation view being a mirror image thereof;

FIG. 5 is a top plan view thereof; and,

FIG. 6 is a bottom plan view thereof.

The broken lines in the figures are for the purpose of showing environmental structure and form no part of the claimed design.
